CONDUCTING HOLDER FOR LUMINOUS
TUBE TERMINALS

Lewis F. R. Bellows, Detroit, Mich.

Application March 2, 1937, Serial No. 128,660

2 Claims. (Cl. 173—328)

This invention relates to luminous tubes, and more particularly to means for holding or supporting such tubes through cooperation with the electrode connections or terminals thereof in such manner as to maintain efficient and flexible electrical contact therewith.

Luminous tubes are used chiefly in electric signs or similar electrical displays, and a single tube may embrace several characters or units of a sign or design, or it may constitute a part, or the whole, of an individual character or unit, depending upon the size of the display. In any event, each tube includes two or more electrode connections or so-called terminals, and in the fabrication of the sign or other display device, the terminals, disposed at right angles to the body portions of the tubes, are adapted to be passed through apertures in a metal backing plate and connected rearwardly thereof with electrical conductors, it being common in prior constructions to line the apertures through which the terminals are extended with relatively long bushings of porcelain or other suitable material. Tubes that are especially long are commonly supported intermediate their ends by suitable means projecting from the front face of the backing plate.

With respect to such prior constructions as above referred to it may be pointed out that an accumulation of moisture on the tubes and within the aforesaid bushings adjacent the terminals frequently results in a complete grounding of the circuit or at least a leakage of current with a consequential destruction or impairment of the effectiveness of the tube.

A principal object of my invention is to eliminate the aforesaid bushings, leaving only the narrow walls that define the apertures surrounding the tube, and to support the tubes substantially central of the apertures or in materially spaced relation to said narrow walls, thereby to maintain an air gap of appreciable width, desirably not less than one-eighth of an inch, between the tube and the surrounding metal, the area of said walls being so slight, due to the thinness of the backing plate, that an accumulation or building up of moisture thereon to an extent sufficient to bridge said air gap is prevented.

Another object of my invention is to provide a yielding holder or support wherewith the terminal of the tube is engaged that, by reason of its yielding character, allows for expansion, contraction and vibration of the tube, reducing to a minimum the liability of breakage from these causes. Also, it permits reasonable self-adjustment of a tube to a plurality of holders, and compensates for any

slight irregularities in the tube and its supports.

A further object of the invention is to provide a comparatively simple yet highly effectual electrical connection between the tube terminal and conductor that affords a multiplicity of contacts thereby to insure ample carrying capacity at all times.

A further object is to provide a simple construction that facilitates longitudinal adjustment of the terminal with relation to its holder or support.

In display devices of the kind wherewith the invention is concerned, it is essential that the conductors carrying the required high voltage current be well supported in properly spaced relation to and effectively insulated from the metal backing plate.

It is a further object of my invention, therefore, to provide a construction that affords adequate insulation and firm support and accurate positioning of the conductors.

Additional objects of a more specific nature are the production of an efficient insulating post for supporting the high voltage conductors, the same comprising a porcelain body having not only a heavily glazed exterior surface but incorporating intermediate its ends a transversely disposed thick stratum of glaze that acts as a barrier to prevent transmission of moisture by absorption endwise through the body in case of penetration through accidental cracks or voids in the exterior coating; to combine with an insulating post of glazed porcelain or the like, a metallic mounting that constitutes the means for attaching the electrical conductor or conductors to the post without destroying or penetrating the glaze, the same including a base that depends exclusively on an interlocking engagement with the post for its attachment thereto, the nature of the interlocking engagement minimizing the liability of cracking or breaking the glazed coating; to incorporate in said mounting, clamping plates attached to the base by screws whose ends occupy, normally in spaced relation to the walls thereof, recesses in the insulating post so as to avoid strains being imposed upon the post while positively preventing dislodgment of the base therefrom; to provide electrical conductors and clamping means therefor characterized by cooperating parts so shaped as to positively prevent turning of the conductors within said means; to form each conductor with an eye and to surround the portion defining said eye with a helical tension spring whereby the spring is constituted an annulus within which a tube terminal may be engaged, this construction being responsible for the yielding support and

the multiplicity of contacts for the electrode connections or terminals more generally referred to hereinbefore; to form the electrode connection or terminal of the tube with a circumferential groove for the reception of the coil spring so as to better hold the terminal and to increase the contact area between it and the spring; and, preferably, to provide a series of such grooves spaced apart longitudinally of the terminal, whereby the terminal 10 may be held in various positions of longitudinal adjustment.

The objects and advantages above enumerated, with others hereinafter appearing, are attained in the embodiment of the invention illustrated in the 15 accompanying drawings, wherein like reference characters designate corresponding parts throughout the several views.

In the drawings, Fig. 1 is a fragmentary rear elevation of a luminous tube sign incorporating my improvements; Fig. 2 is a section on the line 20 2-2 of Fig. 1, this and the succeeding views showing the actual sizes of the parts as used in practice; Fig. 3 is a plan view of the parts shown in Fig. 2, omitting the backing plate and parts there- 25 beyond; Figs. 4 and 5 are sections on the respective lines 4-4 and 5-5 of Fig. 2; Fig. 6 is a fragmentary elevational view of the insulating post with two conductors clamped thereto, and Fig. 7 is a plan view of the insulating post with the 30 clamping plates and screws omitted and a part of the base of the conductor clamp broken away.

In the example selected for illustrative purposes and shown in the drawings, the display device consists of a sign in which each individual 35 letter is formed by a single tube incorporating two electrode connections or terminals. The metal backing plate, designated 1, is provided with apertures 2 through which the electrode connections or terminals 3 of the luminous tubes 4 are adapt- 40 ed to be extended, when applying said tubes to the front face of the backing plate. The portions of the tubes constituting the letters are spaced from, and secured to, the front face of the backing plate at points intermediate their 45 ends by posts or supports 5 to the outer ends of which the tubes are connected by wires 6. The posts 5 may be of any approved type and suitably fastened to the backing plate.

Secured, as by bolts 9, to the rear side of the 50 backing plate 1 in convenient relation to the apertures 2 are insulating posts 10. As best shown in Figs. 2 and 4, the body of each post is made up of sections 10^a and 10^b. These sections are preferably made of porcelain. As is commonly 55 known, this material is absorbent and is suitable for insulators only when properly glazed. In the manufacture of my improved insulating post, a heavy coating of glazing material is applied to the entire surface of each section 10^a and 10^b, and the protruding portion 10^c of the section 10^b is engaged within the recess 10^d of the section 10^a—these parts preferably being other than circular in face view and complementary to each other so as to hold the sections in a definite 65 relation—and the assembly, desirably in an inverted position, is then fired. This fuses the glazing material, causing that on the interengaging parts of the two sections to amalgamate, and that on the adjacent external surfaces of said 70 sections to flow together at the joint between the sections, thus producing an especially thick coating at this point. Now in case the glaze of either section becomes chipped or cracked, or in the event of a void in the external coating of either section, any moisture admitted to the body 75

portion of the affected section will not reach the other section because of the stratum of glaze between the two sections.

The post 10 terminates at its upper end in a boss 11 that is rectangular in plan and has beads 12 at its ends. These beads are interrupted at about their middle by a groove or recess 13, and are undercut at 14 where their outer surfaces merge into that of the adjacent part of the post.

Laterally engaged with a pressed fit over the 10 boss 11 is the base 15 of conductor attaching means, the same including also clamping plates or jaws 16. The ends of the base 15 are formed to embrace the beads 12, and at like distances from, and on opposite sides of, its transverse center the base is formed with parallel grooves 17 that extend the full width of the base and are preferably V-shaped in cross section. Similar grooves 18 are formed along the inner edges of the clamping plates 16 in opposed relation to the 20 grooves of the base. The outer edges of the clamping plates are turned downwardly and bear on the adjacent end portions of the base. Screws 20 pass freely through holes in the clamping plates and are threaded into tapped holes in the 25 base 15 and therebeyond enter the recesses 13 in the beads 12. While, ordinarily, the inner ends of the screws do not engage the glazed walls of the recesses, they do serve as stops for positively preventing withdrawal of the base 15 from 30 the boss 11 in case undue pressure is applied thereto in a lateral direction.

Adapted to be fastened to the insulating post 10 by the attaching means just described are conductors 25. Each consists of a piece of stiff 35 wire or rod, desirably bronze, that is preferably square, or at least other than circular, in cross section. At one end the conductor is formed to provide an eye 26, the same being shown as in the plane of one of the diagonals of the conductor. Surrounding the portion of the conductor that constitutes the eye 26 is a continuous 40 helical tension spring 27. The two convolutions between which the conductor enters the interior of the spring constantly and firmly bear against 45 the opposite sides of the conductor so that good electrical contact between the spring and conductor is always maintained at these two points, regardless of any lateral movement of the spring with respect to the eye. As previously stated, 50 the posts 10 are mounted on the backing plate 1 in convenient relation to the apertures 2. To the insulating post that occupies the lower right hand corner of the backing plate, as the parts are viewed in Fig. 1, is clamped a conductor 25 with 55 its eye 26 substantially in axial alignment with the adjacent aperture 2. The eye is maintained in proximate parallelism with the plane of the backing plate by reason of the fact that the conductor is non-rotatably supported in a given relation to the post 10 between the base 15 and the clamping plate 16 of the conductor attaching means. With respect to the insulating post that is at present under consideration, a flexible conductor 30, through its terminal 31, is connected 60 by one of the screws 20 directly to the base 15, as will clearly appear from Figs. 1, 3 and 4, the clamping plate 16 that would normally occupy this position having been discarded. The eye of this conductor receives one terminal of the 65 luminous tube that constitutes the initial letter of the sign, and the remote terminal of said tube has connection with one of the terminals of the tube that forms the next letter of the sign through two straight conductors that are sup- 70 75

ported in parallel and opposed relation to each other by a post 10 that is shown as located intermediate said terminals.

The successive letters of the present sign are connected in series and it will be observed that some of the conductors 25 are bent so as to adapt them to this particular installation, and it is when a conductor is bent that the non-rotatable connection between it and the insulating post is of special advantage. If the cooperating parts of the conductors and the attaching means were not other than circular in cross section, or so formed as to prevent rotation of the conductors, there would be likelihood of the conductors turning within their clamps and getting out of position.

The electrode connections or terminals 3, in the form of metallic caps applied to the ends of the tubes 4, are shown as provided with series of circumferential grooves 3^a for the reception of the springs 27. The end of each terminal is more or less pointed or convergent to facilitate its entering the annulus formed by the spring, and the terminal may be pushed through the spring until the latter occupies the particular groove 25 that serves to locate the body of the tube in the desired spaced relation to the front face of the backing plate. This spacing varies according to the nature of the display, hence the adjustment afforded by the series of grooves.

Having thus described my invention, what I claim is:

1. In combination, a backing plate having an aperture, a luminous tube adapted to be given any one of a number of configurations supported 5 adjacent but in forwardly spaced relation to the

obverse side of the backing plate, the same having a rearwardly extending terminal projecting in suspension through the aforesaid aperture, the distance at which the tube is spaced from the backing plate depending upon the configuration 5 of the tube, an insulating element mounted upon the reverse side of the backing plate in spaced relation to the aperture, a stiff elongated electrical conductor fixedly attached to the insulating element, and yielding self-contracting receptacle 10 solely sustained by the conductor in approximate alignment with said aperture, the terminal of the tube having a series of longitudinally spaced depressions with a selected one of which said receptacle cooperates.

2. In combination, a backing plate having an aperture, a luminous tube supported forwardly of the obverse side of the backing plate and having a rearwardly extending terminal projecting in suspension through the aforesaid aperture, an 20 insulating element mounted upon the reverse side of the backing plate in arbitrarily spaced relation to the aperture, an elongated electrical conductor consisting of a relatively stiff piece of wire fixedly attached an appreciable distance from 25 one of its ends to the insulating element, and a yielding self-contracting receptacle solely sustained by the aforesaid end of the conductor, the conductor being bendable so as to obtain approximate alignment of the receptacle with said aperture, and the terminal of the tube having a depressed seat spaced from its end for cooperation with the receptacle.
